UNITED STATES PATENT OFFICE.

CHARLIE B. MOORE, OF ALTOONA, PENNSYLVANIA.

CAR COUPLER.

Application filed February 28, 1925. Serial No. 11,777.

To all whom it may concern:

Be it known that I, CHARLIE B. MOORE, a citizen of the United States, residing at Altoona, in the county of Blair and State of Pennsylvania, have invented certain new and useful Improvements in Car Couplers, of which the following is a specification.

My invention relates to couplers for cars, and more particularly to cars used in coal mines.

The object is to provide a device of this character which will automatically couple the cars when they come together, and will hold them in reliable operative relation to each other, while at the same time permitting the cars to make the short turns, and the abrupt dips incident to the running of cars in mines.

Another object is to provide a device of strong and durable construction which will not only couple automatically, but which can be quickly and easily uncoupled whenever desired.

A further object is to so construct the device that it can be easily adapted to existing cars, just as they are, without having to provide specially constructed parts to receive the device.

Minor objects will appear in the subjoined description.

An important feature of the invention is a semi-cylindrical support for carrying one of the coupler members and forming a universal joint connection between the same and the car.

The invention consists in certain novel features of construction and arrangement of parts, as will be hereinafter described and claimed, reference being had to the accompanying drawings, in which:

Fig. 1 is a top plan view of a pair of my couplers in operative relation to each other.

Fig. 2 is a side elevation of the coupler member, located on one of the cars, with certain parts connected therewith shown in section.

Fig. 3 is a side elevation of the cooperating coupler member located on the other car.

Fig. 4 is a side elevation of the spring carried on the last named coupler for yieldingly holding the two coupler members against accidental disengagement from each other.

Fig. 5 is a top plan view of the wear plate of the first named coupler member and is secured to the bottom of the car.

Fig. 6 is a brace plate for the vertical bolt of the semi-cylindrical coupling-hook support.

Fig. 7 is a perspective view, on a somewhat enlarged scale, showing said support in inverted position; and,

Fig. 8 is a perspective showing the same in its upright position.

Referring further to the drawings, the numeral 1 indicates the front end of a floor of a mine car, and 2, the bumper plate thereon. 3 indicates the wear plate of my device which is rigidly secured to the floor 1 of the car, and is provided with openings 4 for the reception of suitable securing bolts. This plate 3 is also provided with a central opening 5 for the reception of the projection 6 on the lower side of the semi-cylindrical support 7; and with two integral upwardly extending projections or standards 8 at its forward corners. The downwardly projecting portion 6 of the support 7 is provided with a central opening 9 which extends through the bottom of the chair, and in this opening is received the sleeve 10 which extends on down through a registering opening provided therefor in the bottom of the car. This sleeve 10 forms a bushing for the bolt 11 which is employed to hold the support 7 rotatably mounted on the wear-plate 3. The brace-plate 12 is provided at its forward end with an opening 13 which engages the upper end of the bolt 11 to brace the same against rocking in its bearings. At its upper end this brace-plate is provided with openings 14 for securing the same to the floor of the car.

The support 7 is provided at its sides with aligned horizontal openings 15 for the reception of a journal 16 which is secured by a set-screw 17 in an opening 18 at the inner end 20 of the coupler member, 19, which rear end is of a size to be easily received into the chair 7 between the sides 16 thereof with plenty of room left for play to allow said coupler member to be rocked up and down on the journal 18. In advance of the outer end of the support 7, this coupler 19 has a downwardly projecting portion 21 which rests upon the wear plate to move horizontally thereon. From the construction described, it will be seen that while the coupler member 19 can rock up and down on the journal 18, it can also, by means of its connection through said journal with the support 7, rock with said chair in a

horizontal direction on the bolt 11, thus providing for the universal movement of the inner end of said coupler member 19.

Since the brace-plate 12 is held in fixed relation to the support 7, the outer end of said brace-plate is reduced in width, as at 22, to prevent it from interfering with the horizontal rotation of the support on the bolt 11. At its outer end this coupler member 19 is provided with a handle 23 for raising said end to uncouple its hook 24 from the corresponding hook 25 of the co-operating coupler member 26, which is provided at its other end with a flattened portion 27 provided with openings 28 for securing the member to the bottom of the car to which it is to be attached. This flattened portion 27 is provided at its inner side with an integral upwardly extending flange 29 provided with bores 30 by means of which the spring 31 is secured to said flange, the spring having corresponding bores 32 therein as clearly shown in Fig. 4, the object of this spring being to hold the two coupler members against accidental disengagement, as illustrated in Fig. 1.

The spring 31 is curved outwardly at its outer end to provide said end on its inner face with the curved surface 33 adapted to be engaged by the forward end of the coupler member 19 as the two coupler members come together for interlocking engagement, as illustrated in Fig. 1. When the members are thus coupled, the spring 31 presses the coupling member 19 against the co-operating coupler member 26, so that the two cannot become accidentally disengaged. If due to the irregularities of the track, one car drops a little below the other, the ends of the hooks on the coupler members being rounded, as illustrated at 34 in Fig. 2, permits said coupler hooks to easily move vertically upon each other as much as may be required.

In case of the cars running around sharp curves, the support 7 rocks on the bolt 11 and permits all the play required. Springs 35 are bolted at their bent ends 35^a to the rigid standards 8 of the wear plate 3, and these springs press the outer sides of the chair 7 and normally lie in flat engagement with said sides, and thus resist the turning movement of said chair sufficiently to return it to its normal position when the curve has been passed and the cars have again come into alignment with each other.

Special attention is called to the fact that the device is adapted to the cars now in common use, so that no change has to be made in the cars in order to attach my device in operative position thereon.

Attention is also called to the fact that the couplers are so mounted on the cars that the regular car bumpers absorb all the bumping strain in the usual way, and the

couplers therefore do not receive any of the coupling strain.

When it is desired to uncouple the cars, the coupling member 19 is simply lifted by means of the handle 23 thereof, out of engagement with the cooperating coupler member 26. When the handle 23 is released by the operator the member 19 drops by gravity into position to reengage the coupling member 26 when the cars are again bumped together, the projection 21 of said member 19 forming a stop for limiting the downward movement of said member.

It is apparent that any of the well known arrangements for lifting the coupling pins of couplers, from the side of the car, may be employed to engage the handle 23 of my device to uncouple the car, but as accessories of this character are common with couplers, it is not deemed necessary to illustrate such an arrangement.

From the foregoing, it will be seen that I have provided a device which is quick, convenient, and reliable in its operation, and which saves much time in the coupling and uncoupling of the cars in operating the mines.

Having now described my invention, what I claim as new and desire to protect by Letters Patent is:—

1. In a device of the character described, the combination with one of the coupling members, of a wear-plate adapted to be secured to the floor of a car; a U-shaped coupler support horizontally rotatable on said plate; a horizontal journal for connecting said support with one of the coupler members; and opposing springs for pressing the U-shaped member to yieldingly hold the same in a fixed position. 105

2. In a device of the character described, the combination with one of the coupling members, of a U-shaped support therefor; a wear-plate upon which said support is mounted, said plate being adapted to be secured to the floor of the car; means for rocking the coupling member up and down on the U-shaped support, said support being mounted for horizontal rotation on the wear-plate; and springs carried on the wear plate 115 for pressing opposite sides of the U-shaped member to yieldingly bias the same against horizontal rotation.

3. In a device of the character described, a wear plate adapted to be secured to the floor of the car; a U-shaped coupler support on the wear-plate; a vertical bolt extending through the bottom of said U-shaped member, the wear-plate, and the floor of the car; a brace plate extending into the U-shaped member and pivotally engaging the upper end of said bolt to hold the same against rocking strain in said U-shaped member; springs on opposite sides of the U-shaped member for holding the same in 130

longitudinal alinement with said brace-
plate; a horizontal journal in the cou-
pler support above said vertical bolt; and a
coupler member rotatably held by said hori-
5 zontal journal.

4. In a device of the character described,
the combination with a coupling member,
of a U-shaped support having a horizontal
journal for the coupling member; a sup-
10 porting plate upon which the U-shaped sup-

port is mounted for horizontal rotation;
springs carried by the supporting plate for
pressing the U-shaped support to bias the
same against rotation on the plate; a co-
operating coupling member; and means for 15
yieldingly holding the coupling members
against accidental disengagement with each
other.

In testimony whereof I affix my signature.

CHARLIE B. MOORE.
